MECHANISM FOR OPERATING UPON WARP-THREADS OR THE LIKE.

1,344,795.

Specification of Letters Patent. Patented June 29, 1920.

Application filed February 23, 1905. Serial No. 246,831.

To all whom it may concern:

Be it known that we, MILLARD F. FIELD and CHARLES D. LANNING, citizens of the United States, both residing at Boston, in the county of Suffolk, Commonwealth of Massachusetts, have invented an Improvement in Mechanism for Operating upon Warp-Threads or the like, of which the following description, in connection with the accompanying drawings, is a specification, like letters on the drawings representing like parts.

Our invention consists in improvements in mechanism for acting upon a series of elements such as the threads of a warp and is intended more particularly to provide means for maintaining a coöperative alinement between a progressively acting operating mechanism such for example as the needle of a warp drawing machine and the individual members of two or more separate groups of elements, which members are intended simultaneously to be acted upon by said operating mechanism. Such by way of illustration may be the threads of the warp, the series of heddles in the harness and the splits of the reed in the warp drawing machine referred to.

Our invention is not limited in its application to any particular purpose or to any particular machine or apparatus but by way of illustration, in the accompanying drawings we have shown one form of the same embodied in a well-known type of warp drawing machine, many features of which are shown in patent to M. F. Field No. 755,861, dated March 29, 1904.

In a warp drawing machine as ordinarily constructed, the warp threads are held distended in a generally parallel relation and adjacent to the warp is arranged the harness and the reed in the same general relation which they are to occupy in the loom. Operating mechanism comprising a needle or hook and appropriate driving mechanism upon a moving carriage is given a progressive step by step movement crosswise the reed, the harness and the warp, at each advance of the carriage the needle being caused to move forward between the splits of the reed, through the eye of the heddle to seize one of the warp threads and draw the said

thread back again through the heddle eye and the reed. The carriage then advances to permit a repetition of the same operation upon the next adjoining thread. In the warp drawing machine as generally constructed, the step-by-step advance of the operating mechanism is designed with reference to the spacing of the heddles and, if this be different from the spacing of the warp threads or the reed splits, some corrective or compensating movement of the warp threads or the reed or both with reference to the heddles becomes necessary. Ordinarily the total width of the warp is materially greater than the total width of the harness and frequently the warp threads are irregularly spaced, in the one case causing the warp threads to increasingly depart from correct alinement with the operating mechanism, and in the other causing irregular departures from the proper alinement.

In the accompanying drawings we have shown one embodiment of our invention applied to a warp drawing machine, so that the individual members of the heddles and the warp threads and the reed splits are brought into coöperative alinement with the operating mechanism to permit the latter to act simultaneously upon the individual members of these three groups of elements, even though the latter tend normally to be out of alinement with each other.

Our invention will be best understood by reference to the following description, taken in connection with the accompanying drawings, which show, for illustrative purposes, one embodiment thereof; while its scope will be more particularly pointed out in the appended claims.

In the drawings,—

Figure 1 is an end elevation partially in section showing a warp drawing-in machine to which has been applied one form of our invention;

Fig. 2 is a plan view of the same partially broken away;

Fig. 3 is a rear elevation showing parts of the corrective feeding mechanism detached from the remainder of the machine;

Fig. 4 is a sectional side elevation of the same;

Fig. 5 is a view in perspective showing the relation of the compensating governing mechanism to the warp threads; and,

Fig. 6 is a detail in section showing the 5 feed pinion of the warp carriage.

In the drawings we have shown a warp drawing machine of the general type illustrated in patent to M. F. Field No. 755,861. The general function of this machine is to 10 support the warp, the harness and the reed in the general relation which they will subsequently occupy in the loom and there to permit appropriate mechanism to draw the individual threads of the warp through the 15 appropriate heddle of the harness and between the splits of the reed preparatory to placing these several elements with the drawn warp in the loom.

For a description of the details of the 20 operation of this machine reference may be had to the above-mentioned patent, it being sufficient for the purposes of our invention here to point out only the general operation thereof. The harnesses, of which herein 25 there are two,—a front set *a* and a rear set *a'*, and the reed *b* are suitably supported transverse to the line of action of the drawing-in needle *c*, which latter is mounted for reciprocal movement, together with the 30 needle operating mechanism upon the traveling carriage *d*. The latter is mounted to travel through a step-by-step movement upon suitable ways lengthwise the frame of the machine and parallel with the reed and harness, the mechanism for reciprocating the 35 needle and advancing the carriage at appropriate times being actuated from driving shaft *d'* moving with the carriage and receiving its movement from some suitable 40 source (not shown). When the needle is ready for its forward movement upon the carriage, the arm *b'* is caused to move forward to separate the splits of the reed at the appropriate point so that the needle may 45 with certainty pass through the desired space therein. As in the prior patent referred to the reed is supported somewhat loosely upon bearings *b* permitting it to yield or slide longitudinally so that if the 50 splits are irregularly spaced or for any reason out of alignment with reference to the heddles the reed frame will be given a slight longitudinal movement by the arm *b'* which has an appropriately shaped nose, to bring 55 the same with certainty into correct alignment for the action of the operating mechanism.

Suitable harness spreading and separating mechanism *a*, fully disclosed in the said 60 prior patent, advancing with the carriage and bearing a definite relation thereto, is caused intermittently to act upon the successive heddles of the harness so that the appropriate heddle eye through which the 65 warp thread is to be drawn is separated in

turn from the others and held within the path of the advancing needle.

When the needle advances it passes between the separated and properly aligned reed splits, and through the appropriate 70 heddle eye, which latter is maintained by the separating mechanism in certain alignment with reference to the needle path. Further advancing the needle is caused to partially turn and seize a warp thread the latter being shown with reference to the reed and the harness eyes at *e* (Fig. 1). The needle is then immediately retracted drawing the thread through the heddle eye and between the splits of the reed, the thread being disengaged from the needle by a transverse movement of the knock-off finger *d*. The needle having been fully retracted, the carriage is advanced another step, the arm *b'* moved into the next adjacent space between 75 the reed splits and the harness separating mechanism turned to maintain the next successive heddle eye in the advanced path of the needle. The operation is then repeated and again repeated until the entire warp has 80 been drawn through the harness and the reed.

The warp threads pass upward from the warp beam (not shown) through a gripping member or bar *e'* (Figs. 1 and 5) over a shaft *e* which carries means for first stretching and then separating the threads, and to a second gripping member or bar *e*. The gripping member *e* clasps the threads with a relatively slight friction but the gripping member *e'* with a relatively greater friction, so that as the threads are seized and drawn by the needle the loose ends thereof pass readily from the gripping member *e* but remain firmly held in the gripping member *e'*. The action of the machine so far described and the general construction and arrangement of parts is substantially that of the well known warp drawing machine a type of which is disclosed in the prior patent referred to.

The warp separating device *e* herein comprises spreading and separating means carried upon the shaft *e*, the latter being journaled in hangers carried by the standards *d* secured to and traveling with the carriage *d*, one of the said standards being shown in Figs. 1, 3 and 5.

The separating mechanism is therefore caused to advance with the carriage and act upon the successive threads of the warp, said shaft *e* being given an intermittent rotation in a well known way by gearing driven from the carriage. Referring to Fig. 5, the action of the warp separating device will be 120 readily understood. The shaft *e* toward its active end is of increasing diameter and, as it advances beneath the threads of the warp, gradually increases the tension thereupon, suitable corrugations *e* being pro- 125

vided to stroke the threads into parallel position. As the carriage and shaft f^2 advance the successive warp threads engage the lip of the warp separating feed screw 5 portion e^6 and are selected and separated one at a time and advanced by the intermittent rotation of the screw until they reach the final position of the warp thread e . The separating screw having a fixed relation with 10 reference to the carriage and therefore to the path of the needle the final position assumed by the thread may be and is made to lie with certainty within the needle path.

It will be seen that where the width of the 15 warp is greater than the width of the series of heddles in each harness, the successive warp threads will depart more and more from a position of alinement with the corresponding heddles and from alinement with 20 the needle which latter advances at each operation just enough to pass through the next separated heddle eye. Although the warp thread separating screw will tend to bring the warp threads into a position of alinement 25 with the needle yet if the warp is unmoved its threads become more remote with reference to the feeding screw itself as the operation proceeds. It is found to be important for the effective action of the separating device that the warp threads should 30 meet the screw e^6 at an angle which approximates the pitch of the screw thread, but if the warp threads are fixed in position this angle will continually decrease and 35 will soon become too little to permit separation of the thread by the screw.

In order to provide a corrective movement to correct the changing relation between the operating mechanism and the 40 warp threads, the warp beam and the gripping bars e' and e^3 are mounted upon a frame or carriage, which can be moved lengthwise the machine to provide the necessary compensating movement for the 45 warp.

Referring to Figs. 3 and 4, wherein the construction of one end of this frame or carriage is partially shown, the latter consists of the two end supports e^7 which are 50 hung upon the horizontal rods e^8 , the latter adapted to move lengthwise over the horizontal grooved guiding rollers e^9 . The clamp bar e' is secured directly to the end piece e^7 , while the clamp bar e^3 is adjustably 55 pivoted upon the rod e^{10} , the latter being secured to the said end piece e^7 . The opposite end of the carriage is similarly constructed. The compensating adjustment of the warp carriage may be manually effected 60 through the rotatable rod f (Figs. 3 and 4), the latter being geared by the beveled gears f' to the vertical shaft f^2 , the lower end of the said shaft f^2 having secured thereon the pulley f^3 . An endless band f^x embraces the 65 pulley f^3 and a corresponding pulley (see

Fig. 2) at the opposite end of the machine, passing about the vertical guide pulleys f^4 , f^4 carried upon the standard d^3 . The said guide pulleys serve to maintain the band in frictional contact with the band 70 wheel or pulley f^5 . The latter is removably but rigidly secured (Fig. 6) as by means of the pins f^7 to rotate with the pinion f^6 , the teeth of the said pinion being in engagement with the rack r (Fig. 2) secured to and movable with the warp carriage. If now the roll or rod f is turned by hand the vertical shaft f^2 and pulley f^3 75 is also turned, and movement of the band f^x effected. This turns the pinion f^6 , and 80 causes the longitudinally movable warp carriage laterally to advance or recede relatively to the pinion and therefore to the operating carriage d which carries the pinion. Thus, in the machine illustrated 85 the position of the warp may be adjusted from time to time by hand to compensate either for irregularities in the spacing of the warp threads or to offset the continually advancing position which the said warp 90 threads bear to the operating mechanism as the drawing-in operation proceeds.

For greater efficiency however, this corrective movement should be automatic and regulated by the progress of the drawing-in 95 operation and in the machine illustrated we have provided means which act automatically to move the warp, such means being thrown into and out of operation by the charging position of a feeler finger, the latter being controlled by the position of the warp threads relatively to the operating mechanism. This is accomplished in the following manner: The shaft g to which is keyed the band wheel f^5 passes downward 100 beneath its supporting frame and is rigidly secured to the ratchet wheel g' , whereby a turning of the latter will cause the corresponding movement of the pinion f^6 and a compensating movement of the warp carriage. 105 The turn of the ratchet wheel is effected by a pawl h (Fig. 1), pivoted upon the reciprocating pawl actuating rod h' , the latter being connected to the oscillating link h^2 , the latter moved by the rod h^3 , connected to the needle actuating lever h^4 . The connection is such that when the needle is moved inwardly the pawl actuating rod is also moved inwardly and carries the pawl 110 idly over the teeth of the ratchet wheel. When 115 the needle is retracted the pawl actuating rod is also retracted, and if the pawl is permitted to engage with the teeth of the ratchet wheel it effects a slight movement of the ratchet wheel and therefore of the 120 warp carriage, as described. The compensating movement of the warp carriage is therefore effected as it should be while the 125 needle is in its retracted position.

The means which automatically control 130

the operation of this warp compensating mechanism, is as follows. Swingly mounted upon the arm d^4 of the mechanism carriage, is the feeler finger i , having a 5 properly shaped nose i' correctly positioned to underlie the foremost of the warp threads provided the latter are in the correct or the desired alinement with reference to the separating screw e^4 or other elements of the 10 operating mechanism. In Figs. 4 and 5 the warp threads are illustrated as having the desired relation to the separating screw, and the nose i' of the swinging finger is held downward against the under side of the 15 foremost warp threads, causing its opposite and angularly turned end i^2 to bear against the heel of the pawl lifting lever k , which is fulcrumed upon the pawl actuating rod h' . The lever k is provided with a pawl lifting 20 finger k' , which has an inturned end engaging a curved slot h^5 in the pawl, the proportions of these several parts being such that when the nose of the feeler is held downward by contact with the warp threads, the 25 lifting lever K is forced backward and the pawl maintained out of engagement with the teeth of the ratchet wheel g' , the reciprocations of the pawl actuating rod being ineffective to cause movement of the warp 30 carriage.

As the drawing-in operation proceeds, the warp threads will become farther advanced relatively to the needle and the nose of the feeler finger and their angle of inclination 35 to the separating screw less, so that finally the withdrawal of the foremost warp thread will free the feeler and the advance of the operating carriage will be insufficient to bring its nose under the next succeeding 40 warp thread. The finger will then move to the position shown in Fig. 1, permitting the lifting lever k to swing forward and drop the pawl into engagement with the teeth of the ratchet wheel. The weights of the parts 45 can be so adjusted as to permit the nose of the feeler finger to press upward against the warp threads with any desired tension, but preferably they are proportioned to permit the pawl slightly to overbalance the finger 50 so that the upward tendency of the latter is relatively slight and slight variations in the tension of the warp threads will not affect the operation of the device. When the feeler finger moves to the position shown 55 in Fig. 1, each reciprocation of the pawl moves the warp carriage slightly from right to left, as viewed in Fig. 5, and this compensating movement will continue by repeated slight increments until the desired 60 alinement of the warp in the separating mechanism is obtained. Each retraction of the pawl operating rod h' is accompanied by rearward movement of the lifting finger k , and the inturned end i^2 , of the feeler 65 finger, so that the nose i' of the latter moves

from a position above the plane of the warp threads on advancement of the pawl to a position below the plane of the same on retraction of the pawl. If the corrective movement occasioned by the retraction of the pawl is sufficient to bring the next warp thread within the path of movement of the feeler finger nose, movement of the latter is arrested on the advancing of the pawl and the latter is again withdrawn from engagement with the teeth of the ratchet wheel and into the position shown in Fig. 4. Thus it will be seen that the nose of the feeler finger being located in the place where the foremost warp thread ought to be for the best 80 conditions of operation, if the foremost warp thread is not in its designed position in contact with the feeler finger, the warp carriage will be automatically adjusted through a step-by-step compensating movement to bring the leading warp thread into the desired position.

In the description of the machine, it has been assumed that the endless band f^x has no effect upon the automatic feed of the warp carriage, and in fact this is the case in the machine illustrated, for, by reference to Fig. 6, it will be seen that the pitch circle of the band wheel f^5 is substantially equal to the pitch diameter of the pinion f^6 , so that as the operating carriage moves the pinion and band wheel along, the former will roll idly upon the rack and the latter upon the endless band.

If the total width of the warp is less than the total width of the harness, instead of greater, as has hereinbefore been assumed, the resultant compensating warp feed must be in the opposite direction to that described, that is to say, as the drawing in operation 100 progresses, the position of the warp threads will lag behind that of the corresponding heddles and the inclination between the warp threads and the separating mechanism will become greater and greater. To correct this the warp should be moved from left to right, as viewed from the rear in Fig. 5, instead of in the opposite direction. In order that this may be effected by the same mechanism as has been described, we have 105 provided means so that the step-by-step movement of the operating carriage from left to right (as viewed from the rear in Fig. 5) may be made to cause a step-by-step movement of the warp in the same direction but farther than is required to compensate for the increase in pitch of the warp threads, the automatic compensating feed when brought into action by the feeler finger 110 being then permitted to move the warp carriage back again from right to left by an increment which is sufficient always to insure the correct alinement of the warp threads.

To accomplish this, the band wheel f^5 is 115

removably mounted on the shaft g and may be replaced by one having a greater pitch diameter than that shown in Fig. 6. If this is done, each step-by-step advance of the 5 operating carriage which carries the shaft g will cause a smaller angular movement of the band wheel than before, consequently the pinion f^6 will roll idly upon the rack r to a lesser extent and will cause the rack r to move from left to right and thus carry 10 the warp along in the direction of travel of the mechanism carriage. The amount of this movement which is dependent upon the size of the band wheel f^6 is preferably greater 15 by a slight increment than is necessary to properly adjust the warp and on the next retraction of the needle, if the movement of the warp has been too great and the foremost thread thereof is not in proper alignment, the rise of the feeler finger will throw 20 in the automatic compensating movement for the warp.

It is to be observed that in the specific embodiment of our invention illustrated, the 25 warp carriage is positively positioned relatively to the mechanism carriage by the compensating motive mechanism, and that this motive mechanism is at all times under the control of the delicately adjustable feel- 30 ing means. The latter may, of course, be embodied in a great variety of forms. The feeler finger or member has a movement transverse to or crosswise of or to and from the plane of the warp, instead of in or sub- 35 stantially in the plane thereof. It will be evident from the foregoing description and from the illustration, and particularly Fig. 5, that the nose or operative portion of the feeler finger contacts with a plurality of the 40 leading warp threads. This construction is of importance and is preferably employed by us. A feeler finger vibrating or moving in the plane of the warp tends to roll the thread back from the point of action of 45 the separating mechanism, and tends to roll them over one another. This action is eliminated or prevented when the feeler finger works across or transversely of or to and from the plane of the warp. It will also 50 be observed, viewing Figs. 4 and 5, that the feeler is made operative upon the thread at a point relatively remote from the point of action of the separating mechanism. This is of practical importance, inasmuch as the 55 operation and character of the warp separating mechanism herein illustrated are not dependent upon the controlling with absolute nicety of the slope of the threads to be separated. The feeler finger therefore may 60 advantageously be located at a point relatively remote from the point of action of the warp separating mechanism. Furthermore, the feeler finger need not work so accurately as if the thread next to be separated or 65 picked off had to be located with great ex-

actness by the action of the separating mechanism.

These principles and features of operation of the feeler finger or member may be employed, within the scope of our invention, 70 in various types of warp separating or selecting machines, and we are therefore not limited to the use thereof in connection with a mechanism of the drawing in type.

Obviously, the presence or absence of the 75 warp threads might be made to control this mechanism by either stopping or starting the movement of the feeler finger, or by acting upon the motive mechanism in any way to throw it in or out of operation at the de- 80 sired times. A construction like the one shown, however, has the advantage of simplicity, delicate adjustment and sensitiveness. The vibratory movement of the feeler and its connection to the reciprocating driv- 85 ing mechanism of the needle is advantageous also, in that the control of the feeler finger over the operative connections between the reciprocating mechanism and the compensating mechanism is periodic and times the 90 advance of the warp carriage relatively to the needle carriage exactly with the retrac- tions of the needle.

We have here described one embodiment 95 of our invention as applied to a common type of warp drawing machine. It is to be understood however, that it is shown of the construction and in the connection described for illustrative purposes only and is not limited to the particular details or the special 100 use referred to herein, but on the contrary is susceptible of application to other uses which will be apparent to those skilled in the art, wide departures from the construction and arrangement disclosed, and of embodiment 105 in a variety of forms to which reference here is unnecessary.

Claims:

1. In a machine for operating upon warp threads, the combination with a warp carriage of mechanism for operating upon the threads including a warp thread separating worm adapted to pick off or select the threads one by one, a thread taking member to take the threads from the separating 110 worm the latter being adapted to feed toward said thread taking member a plurality of selected threads at a time in controlled and separated relation, a feeler member adapted to engage a plurality of the threads so controlled by said worm, and means controlled by said feeler member for effecting a compensating adjustment of the warp support with relation to said worm.

2. In a machine for operating upon warp 125 threads the combination with a warp carriage, of means for operating upon the threads including a thread selecting and separating worm, said mechanism having a traversing movement with relation to the 130

- warp carriage, and a feeler finger for effecting a compensating adjustment of the warp carriage.
3. In a machine for operating upon warp threads the combination with a warp carriage, of means for operating upon the threads including a thread selecting and separating worm, said mechanism having a traversing movement with relation to the warp carriage, and a feeler finger for effecting a compensating adjustment of the warp carriage, said feeler having a movement transverse to the plane of the warp.
4. In a machine for operating upon warp threads the combination with a warp support of mechanism for operating upon the warp threads including a thread taking member and means to select the threads one by one and to hold a plurality of selected threads separated and present them in succession to the thread taking member, and a feeler finger adapted to act upon the leading separated thread or threads to adjust the relative position of the warp carriage and the operating mechanism.
5. In a machine for operating upon warp threads the combination with a warp support of mechanism for operating upon the warp threads including a thread taking member and means to select the threads one by one and to hold a plurality of selected threads separated and present them in succession to the thread taking member, and a feeler finger adapted to act upon the leading separated thread or threads to adjust the relative position of the warp carriage and the operating mechanism, said feeler finger having a movement transverse to the plane of the warp.
6. In a machine for operating upon warp threads the combination with a warp support, operating mechanism including thread selecting and separating means adapted to work across the extent of the warp and a feeler adapted to engage a separated thread for adjusting the relation of the warp support to the operating mechanism.
7. In a machine for operating upon warp threads, the combination with a warp support, operating mechanism, feeler finger mechanism for controlling the relation between the operating mechanism and the warp support, gearing through which said feeler mechanism acts and manual adjusting means for moving the warp support also operating through said gearing.
8. In a machine for operating upon warp threads, a warp support, means to operate upon the warp threads in succession, feeding means to impart a movement to the warp support relative to the operating means, means dependent upon the position of the warp threads with relation to the operating means to control automatically the feeding means, and manually operated mechanism 65 to provide an incremental movement for the warp support relative to the operating means.
9. In a warp replenishing machine, a warp carriage to support a transverse section of the warp, a second carriage, thread-selecting mechanism supported thereon to work successively upon said threads, driving mechanism operatively connected to move said second carriage transverse the machine 75 and also connected to impart a feeding movement to the warp-carriage, said driving mechanism also including a feeler finger mounted upon said second carriage and governing the feed for the warp carriage, and manually controlled means to effect a feeding movement of the warp carriage relatively to the second-mentioned carriage.
10. In a machine for operating upon warp threads, the combination with a warp support for holding warp threads distended, of a thread-taking device, operating means therefor, a power-driven means for adjusting the position of the support with relation to the thread-taking device and including a 85 ratchet-and-pawl feeding mechanism and a feeler device having a path of feeling movement transverse the plane of the warp threads for controlling the feeding action of said mechanism.
11. In a textile machine, a warp carriage adapted to hold a series of warp threads distended, means for moving the warp carriage, controlling means adapted to hold the moving means from action including a movable 90 warp-thread feeling member the feeling path of which lies transverse the plane of the warp.
12. In a textile machine, means for supporting a warp with the threads held distended, means for operating upon said threads in succession, means for moving the warp in relation to the operating means, and controlling means for said moving means including a movable, warp-thread, feeling member the feeding path of which lies transverse the plane of the warp.
13. In a textile machine for operating upon warp threads, the combination with a support for a series of parallel elements, operating mechanism, means for adjusting the relation between the operating mechanism and the said support, said means including feeding means and a movable feeler device controlling said feeding means and having a feeling path transverse the plane of said elements.
14. In a warp replenishing machine, a carriage to support a transverse section of a warp with the threads thereof distended in 125 parallel arrangement, a second carriage, thread-selecting mechanism supported thereon to work successively upon said

threads, one main power means, and power-driven means operatively connected to said one main power means and to said carriages to move both of said carriages from said one main power means, said power-driven means including means to move said second carriage transverse the machine, and also including means which include a sensitive feeler finger mounted upon said second-mentioned carriage and having a path of feeling movement across the plane of the warp, to give to said first-mentioned carriage and its contained threads a feeding movement differentially related to the feeding movement of said second-mentioned carriage.

15. In a machine for operating upon warp threads, the combination with a warp support for holding warp threads distended, of a thread-taking device, operating mechanism therefor, thread-separating devices, power driving means for the machine, means actuated by the power driving means for adjusting the position of the support with relation to the thread-taking device and thread-separating devices, and means for governing the action of said adjusting means including a feeler device having a feeling movement across the plane of the warp threads and connections to said power driving means to reciprocatively move said feeler device during the operation of the thread-taking device and thread-separating means.

16. In a textile machine, means for supporting a warp with the warp threads held distended, means for operating upon said threads in succession, moving means for moving the warp in relation to the operating means and controlling means for said moving means including a vibratory, warp-thread, feeling member the feeling path of which lies transverse the plane of the warp and driving connections to vibrate the same.

17. In a machine for operating upon warp threads, a warp support, means to operate upon warp threads held therein in succession, a carriage whereon the operating means is mounted, means to traverse the carriage across the warp, means to impart corrective movement to said warp support, a driving mechanism to actuate said operating means to operate upon the warp threads in succession, a feeler device upon said carriage and connections between the same and said driving mechanism to move the feeler synchronously with the operation of said operating means.

18. In a machine for operating upon warp threads, the combination with a warp support for holding warp threads distended, warp-thread operating mechanism, driving means, means for adjusting the relation between the operating mechanism and the warp support, said means including feeding

devices and a movable feeler device controlling said feeding means and connections to said driving means to reciprocatively move said feeler device with relation to the warp threads.

19. In a machine for operating upon warp threads, the combination with a support for a series of parallel elements, operating mechanism, means for adjusting the relation between the operating mechanism and said support, said means including feeding means and a movable feeler device controlling said feeding means, with driving means to reciprocatively move said feeler device with relation to the warp threads.

20. In a machine for operating upon warp threads, the combination with a warp carriage of an operating carriage, means for giving a feeding movement to said operating carriage, power-driven means on the operating carriage for giving a feeding movement to the warp carriage, connections whereby a movement of the warp carriage may follow the feeding movement of the operating carriage, and a feeler finger controlling the power-driven, warp-carriage, feeding means to impart a further movement to the warp carriage.

21. In a machine for operating upon warp threads, the combination with a warp carriage of an operating carriage, means for giving a feeding movement to said operating carriage, and means including differential gearing between the operating carriage and the warp carriage whereby an incremental movement of the latter may follow the feeding movement of the former.

22. In a machine for operating upon warp threads, the combination with a warp carriage of an operating carriage, means for giving a feeding movement to the operating carriage and means connecting the operating carriage and warp carriage whereby an incremental movement of the warp carriage may follow the feeding movement of the operating carriage, said means being adjustable whereby such incremental movement may be had in either direction.

23. In a warp replenishing machine, a warp carriage to support a transverse section of the warp, a second carriage, thread-selecting mechanism supported thereon to work successively upon said threads, one main power means and power-driven means operatively connected to the said one main power means and to said carriages to move both of said carriages from said one main power means, said power-driven means having means to move said second carriage transverse the machine and also having warp-carriage driving means including a feeler finger mounted upon said second carriage and governing the power-driven feed means for the warp carriage, said warp-

carriage driving means being adapted to impart a feeding movement to the warp carriage transverse the machine differentially related to the feeding movement of the first-mentioned carriage and having also 5 adjustable means whereby a feeding movement may be imparted in the same or opposite direction with relation to the machine as the feeding movement of the second-mentioned carriage.

24. In a machine for operating upon warp threads, the combination with a warp carriage of an operating carriage, power-driven means for giving a feeding movement 15 to said operating carriage, gearing connections between said operating carriage and said warp carriage whereby a movement of the operating carriage may impart a movement to the warp carriage, power-driven 20 feeding means acting through said gearing connections for moving said warp carriage relatively to said operating carriage and a feeler finger engaging the warp and controlling said power-driven feeding means 25 for moving the warp carriage.

25. A machine for operating upon warps having, in combination, a main frame, a mechanism carriage movable along the frame, a warp carriage on the frame, a rack 30 on the warp carriage, a pinion on the mechanism carriage in mesh with the rack, a mem-

ber extending along the frame for actuation by the operator, and driving connections between said member and the pinion.

26. A machine for operating upon warps 35 having, in combination, a main frame, a mechanism carriage movable along the frame, a warp carriage on the frame, a rack on the warp carriage, a pinion on the mechanism carriage in mesh with the rack, an 40 endless flexible element on the main frame arranged to rotate the pinion, and manual means for moving said element.

27. A machine for operating upon warps having, in combination, a main frame, a 45 mechanism carriage movable along the frame, a warp carriage on the frame, a rack on the warp carriage, a pinion on the mechanism carriage in mesh with the rack, an 50 element extending along the frame, a member on the mechanism carriage in rolling contact with said element as the mechanism carriage travels, and a driving connection between said member and the pinion.

In testimony whereof, we have signed our 55 names to this specification, in the presence of two subscribing witnesses.
